MEANS OF CHARGING SOLID MATERIAL
INTO A CONFINED ZONE

Charles H. Angell, Chicago, Ill., assignor to Universal Oil Products Company, Chicago, Ill., a corporation of South Dakota

Application September 20, 1930, Serial No. 483,308

3 Claims. (Cl. 214—18)

This invention relates to a means of charging solid, semi-solid or like material to a confined zone which may be maintained at atmospheric, sub-atmospheric or superatmospheric pressure.

5 One of the difficulties encountered in the commercial application of the many recently developed processes, in which solid or semi-solid materials are themselves treated or utilized to assist in the treatment of other materials, has 10 been the problem of continuously or intermittently supplying such material or mixtures thereof to the zone of treatment without interrupting or interfering with the continuous operation of the process. It is the primary object of the present 15 invention to provide a simple and reliable means for this purpose. As examples of processes wherein my improvements find useful application, I may mention those in which coal, coke, peat, lignite, pitches, tars or mixtures of these alone or 20 with oils or other liquids are treated.

Primarily the invention comprises an apparatus for introducing a solid or semi-solid material, or mixtures containing such materials, from an external zone into a confined zone by introducing 25 it first into an intermediate zone and intermittently isolating said intermediate zone from said external zone, during which isolation period the material is introduced from said intermediate zone into said confined zone.

30 It will be understood that many modified forms of apparatus incorporating the broad principles of the invention may be devised. One specific embodiment of the apparatus, employing reciprocating pistons to move the material, is shown diagrammatically in the attached single drawing to 35 more clearly illustrate the principles of the invention, although the invention is not limited to this or any other specific form of apparatus.

Referring to the drawing, the following description 40 of which will embrace both the apparatus and its mode of operation, the solid or semi-solid material which may be, for example, coal, petroleum coke, gilsonite, fuller's earth, diatomaceous earth, adsorbent clays, catalytic materials, metal 45 particles, or any other solid or semi-solid material or mixtures containing the same, is fed into hopper 1 by any suitable means, not illustrated, such as a belt or bucket conveyor or similar device. Hopper 1 is in direct communication through port 50 2 with cylinder 3, which in turn is connected at one end through wall 4 with a zone of treatment 5 which may be at substantially the same pressure but may be at an increased or decreased pressure relative to that in hopper 1. Pistons 6 55 and 7, 6 being defined as the front piston and 7

the rear piston, are mounted upon a reciprocating shaft 8 which may be driven by any suitable means (not shown) such as, for example, a steam engine such as used on reciprocating pumps or an electric motor actuating the shaft through a crank 60 and connecting rod or rack and pinion. With rod 8 at the extremity of its backward stroke, at which point the space between pistons 6 and 7 is directly opposite port 2, material may be discharged from hopper 1 into the space between 65 the pistons and as the pistons move forward, upon the forward stroke of shaft 8, shield 9, which is attached in this case to piston 7 and moves with the pistons and shaft, closes port 2 preventing further discharge of material from hopper 1 into 70 cylinder 3. The material between pistons 6 and 7 may be carried forwardly by the forward movement of shaft 8 and as piston 6 over-rides the end of cylinder 3 into zone 5 the material confined between the pistons is discharged into this 75 zone. As piston 6 recedes from zone 5, upon the backward stroke of rod 8 after the material has been discharged from between the pistons, it is guided to assist its entrance into cylinder 3 by the flare 10 at the end of said cylinder which insures the proper compression of piston rings 11 80 as they enter the cylinder.

It will be understood that any form of piston rings or piston packing may be used to maintain a tight seal between the pistons and the walls 85 of cylinder 3, and it will also be obvious that the walls of cylinder 3 may be lubricated in any well known manner, not illustrated in the drawing.

It is evident that the pressure in the space 90 between pistons 6 and 7 will be equalized with that in zone 5 as the material is discharged into this zone and that substantially this same pressure will be maintained in the space between the pistons as they recede into cylinder 3. For this 95 reason vent 12, in cylinder 3, may be provided so that the pressure in the space between pistons 6 and 7 may be equalized with that in cylinder 3 and in hopper 1, both of which, in this case, are open to the atmosphere, upon the backward stroke of piston 7 as it passes vent 12.

It will be understood that substantially atmospheric pressure or any pressure above or below atmospheric may be maintained upon zone 5 with substantially atmospheric pressure or any pressure above or below atmospheric upon hopper 1. Normally, there will be a differential pressure between hopper 1, from which the material is supplied, and zone 5, to which the material is supplied although they may be at the same 110

pressure, in which latter case the device illustrated functions as a means of conveying the material from one zone to the other without permitting contamination in the treating zone

5 by the outside atmosphere.

I claim as my invention:

1. In combination with a treating chamber, a feeding hopper, a cylinder communicating said hopper with the chamber, frontward and rearward pistons slidably mounted within said cylinder and a shield carried by the rearward piston.
- 10 2. In combination with a treating chamber,

15

80

a feeding hopper, a cylinder communicating said hopper with the chamber, a rod slidably disposed within said cylinder and a pair of pistons fixedly mounted upon said rod.

3. In combination with a treating chamber, a feeding hopper, a cylinder communicating said hopper with the chamber, a rod slidably disposed within said cylinder, frontward and rearward pistons fixedly mounted upon said rod and a shield carried by the rearward piston.
